(57) **CLAIM**

We claim the ornamental design for a tooth-shaped bottle
cap, as shown and described.

DESCRIPTION

FIG. 1 is a front perspective view of a tooth-shaped bottle
cap.

FIG. 2 is a top plan view of the bottle cap.

FIG. 3 is a front elevational view of the bottle cap.

FIG. 4 is a 45° side elevational view of the bottle cap; and,
FIG. 5 is a bottom plan view of the bottle cap.

The ornamental design which is claimed is shown in solid
lines in the drawings. The broken lines in the drawings are
for illustrative purposes only and form no part of the claimed
design.
